CLAIM

The ornamental design for a rotary cutter deck, as shown and described.

DESCRIPTION

FIG. 1 is a front perspective view of the rotary cutter deck showing our new design;

FIG. 2 is a rear perspective view of the rotary cutter deck;

FIG. 3 is a top plan view of the rotary cutter deck;

FIG. 4 is a bottom plan view of the rotary cutter deck;

FIG. 5 is a front elevational view of the rotary cutter deck;

FIG. 6 is a rear elevational view of the rotary cutter deck;

FIG. 7 is a left side elevation view of the rotary cutter deck;

FIG. 8 is a right side elevational view of the rotary cutter deck; and,

FIG. 9 is a rear perspective view of a second embodiment of the rotary cutter deck showing our new design.

The broken line showing of the three circular openings in FIGS. 1-4 and three circular openings with wheel supports and a tractor hitch in FIG. 9 is included for the purpose of illustrating portions of the rotary cutter deck and forms no part of the claimed design.
